DESIGN FOR A DRESS

Elizabeth M. Ciccone, New York, N. Y.

Application August 7, 1937, Serial No. 70,902

Term of patent 3½ years

To all whom it may concern:

Be it known that I, Elizabeth M. Ciccone, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The waist portion and skirt portion of Fig. 2 are shown separately.

I claim:

The ornamental design for a dress substantially as shown and described.

ELIZABETH M. CICcone.
